LOCK

Crayton J. Dials, San Quentin, Calif.

Application October 1, 1935, Serial No. 43,046

9 Claims. (Cl. 70—108)

This invention relates to locks, and particularly to those of the padlock type.

The main objects of my invention are to provide a lock in which air pressure instead of the usual mechanical connections retracts the lockbolts; and which is so constructed that the lock is pick and tamper proof, and can positively only be opened by the use of a proper key.

A further object of the invention is to produce a simple and inexpensive device and yet one which will be exceedingly effective for the purpose for which it is designed.

These objects I accomplished by means of such structure and relative arrangement of parts as will fully appear by a perusal of the following specification and claims.

In the drawing similar characters of reference indicate corresponding parts in the several views:

Figure 1 is a sectional elevation of my improved lock, with the shackle in locked position and the key removed.

Figure 2 is a similar view, showing the key in place and with the bolts retracted and the shank being retracted.

Figure 3 is a bottom plan view of the lock.

Referring now more particularly to the characters of reference on the drawing, the numeral 1 denotes the body or housing of the lock, which may be a one-piece member and preferably of oblong form as shown in Figure 3.

Formed in the body adjacent its opposite sides are cylindrical bores 2, extending in parallel relation from the top of the body to a point near the bottom thereof. The upper portions of these bores form guides for the lower ends of the U shaped shackle 3 of the lock, while the lower portions form pump cylinders in which plungers 4 of any suitable material are snugly and slidably disposed. Compression springs 5 in the cylinders between the bottom thereof and the plungers act to force the latter upward; the springs becoming slack before the plungers reach the top of the bores, so that they cannot be displaced from position by the springs.

Formed in the body near the top and extending toward each other from and radial with the adjacent sides of the bores 2 are smaller cylinders 6, in which lock bolts 7 are snugly slideable. The outer ends of the bolts are preferably tapered, and are adapted to engage notches 8 cut in the adjacent faces of the legs of the shackle. Springs 9 in the cylinders 6 behind the bolts, urge the latter outwardly and into the notches and when the bolts are thus engaged, the springs 5 hold the plungers 4 against the lower ends of the shackle

legs, thus preventing rattling and holding the shackle snugly in a locked position.

Formed in the body centrally between the bores 2 and projecting upwardly from the bottom of the body is a key socket 10. This is preferably of non-circular tapering form. Air passages 11 lead from the cylinders 6 at their inner ends to the socket 10 near the top and on opposite sides. Other air passages 12 lead from the bottom of the cylinders 2 to the socket 10 near the bottom. Release air passages 13 lead from the socket 10 intermediate its ends to the bores 2 above the bolts, or where such passages communicate with the air pockets formed in the bores by the notches 8 when the shackle is in place. The various air passages are holes drilled through from the outside of the body, the unwanted portions of the drill holes being then plugged up as is commonly done. The cylinders 6 are of course formed in the same way.

A special key 14 is provided for use with the lock, having a stem 15 of the same shape and taper as the socket 10, so as to non-turnably and snugly fit in the same. The stem 15 has passage means 16 drilled therein to establish unbroken communication between the passages 11 and 12, when the key stem is properly inserted, but shutting off the socket ends of the release passages 13.

In operation, the shackle 3 may, of course, be mounted on the body by merely depressing the ends of the shackle into the bores 2 until the bolts engage the notches 8, the bolts retracting as they engage the unnotched portion of the shackle, as usual.

The provision of the release passages 13 enables air in the upper portion of the bores, and which might otherwise be confined by the initial depression of the shackle, to be forced out and into the key socket.

Also, it will be noted that one of the passages 13 terminates at socket 10 between the termination of passages 11. This prevents the lock from being opened by a tapered thimble which might be placed in the socket instead of a key to cover both passages 13 while leaving both passages 11 open, and then applying a suction to the end of the socket to retract the bolts—something which could be done if both passages 13 were below passages 11, but which cannot be done with the arrangement shown, as will be evident.

To open the lock, the shackle is depressed beyond a locking position, or as indicated in dotted lines in Figure 2, and before the key is inserted. This lowers the plungers 4 against the resistance of springs 5, expelling the air from the cylinders 6.

through passages 12 which are now open to atmosphere at socket 10. The key is then inserted, and the shackle is released. The springs 5 then act to lift the plungers, and since the passages 12 are no longer in communication with atmosphere but with the cylinders 6 through passages 11 and key passages 16, a tendency to vacuum is set up in cylinders 6. Since the outer ends of bolts 7 are exposed to atmosphere through notches 8 and the narrow passageways formed between the bores 2 and the loosely fitting shackle, the relatively great air pressure on the outer ends of the bolts will force the same inwardly and clear of the notches 8. The shackle may then be withdrawn, as shown.

When the key is withdrawn, the vacuum tendency is of course broken and the springs 9 immediately force the bolts out. Since the lock bolts and their holding springs are offset and in compartments separate from the socket, they cannot be reached and picked by any tool inserted in the socket, and the use of the proper key, together with the necessary air pressure, are essential to the opening of the lock.

From the foregoing description it will be readily seen that I have produced such a device as substantially fulfills the objects of the invention as set forth herein.

While this specification sets forth in detail the present and preferred construction of the device, still in practice such deviations from such detail may be resorted to as defined by the appended claims.

Having thus described my invention, what I claim as new and useful and desire to secure by Letters Patent is:

1. A lock comprising a body having a blind bore, a shackle slidably and releasably mounted in the bore, a cylinder in the body radially of and extending to the bore near its outer end, a lock bolt 40 slidable in the cylinder, the shackle having a notch in its side with which the outer end of the bolt is engageable and having means to allow of depressing movement of the shackle beyond a bolt engaging position, a plunger in the bore below and engageable with the end of the shackle, a spring yieldably holding the plunger against the shackle, the body having a key socket open at its outer end to atmosphere, an air passage from the bottom of the body bore to said socket, another air passage from the socket to the bottom of the bolt cylinder; said passages being adapted to cooperate with a key stem insertable with a close fit into said socket, the key stem having an air passage to establish direct communication between the socket ends of the first named air passages.

2. A lock comprising a body, a shackle having a leg slidably and removably mounted in the body and having a notch in one side disposed inside the body when the shackle is in position, a lock bolt to releasably engage said notch, a cylinder in the body in which said bolt is slidably mounted, another cylinder in the body, the latter having a key socket, separate air passages from the cylinders to terminations at the walls of said socket, said passages being adapted to cooperate with a key stem to closely fit in said socket, said stem having an air passage to then establish direct communication between the socket ends of

said first named passages, and means operable by the depression of the shackle beyond a locking position and its subsequent release from such depression for setting up a tendency to vacuum in the communicating air passages.

3. A lock comprising a body, a locking bolt mounted therein for movement from a locking to a release position, a cylinder in which the bolt is slidable, said bolt at its outer end being exposed to atmosphere, and manually operable means mounted in the body to set up a negative pressure in the cylinder to cause the bolt to be withdrawn to a release position by atmospheric air pressure on the exposed end of the bolt.

4. A lock comprising a body, a locking bolt 15 mounted therein for movement from a locking to a release position, a cylinder in which the bolt is slidable, said bolt at its outer end being exposed to atmosphere, a normally broken air passage 20 extending in the body from the cylinder behind the bolt, said passage being adapted to cooperate with a removable key having a passage to close the break and complete said air passage, and manually operable means mounted in the body and to which the passage is connected beyond the 25 break to set up a negative pressure in the passage only when the key is in place.

5. A structure as in claim 4, in which said last named means comprises a cylinder to which the end of the air passage furthest from the bolt cylinder is connected, a manually depressible plunger in the cylinder, and a spring to move the plunger in opposition to its depressing movement and away from the passage.

6. A lock comprising a body, a locking bolt 35 mounted therein for movement from a locking to a release position, means mounting the bolt for movement to a release position by air pressure, and manually and selectively operable means mounted in the body to enable such air pressure 40 to function upon the insertion of a key in the body.

7. A lock comprising a body, a shackle releasably mounted on the body, a locking bolt in the body to releasably engage the shackle and then holding the same against release, means mounting the bolt for movement to a release position by air pressure, and means to enable such air pressure to function and including a pump plunger actuated by movement of the shackle in one 50 direction.

8. A lock comprising a body, a shackle releasably mounted on the body, a locking bolt in the body to releasably engage the shackle and then holding the same against release, means mounting the bolt for movement to a release position by air pressure, and means to enable such air pressure to function and including a pump plunger actuated by movement of the shackle in a direction opposite to that necessary to release the 60 shackle from the body.

9. A structure as in claim 2, there being an additional passage from atmosphere to the socket and communicating therewith at a point between the outer end of said socket and the point of termination of the key-cylinder passage in said socket, said additional passage being closed by the key stem when the latter is inserted.
